(57) **CLAIM**

The ornamental design for a candle or tea light holder, as shown and described.

DESCRIPTION

FIG. 1 is a side elevation view of a candle or tea light holder having separate upper and lower portions, showing my new design;

FIG. 2 is a side elevation view of the upper portion of the design illustrated in FIG. 1;

FIG. 3 is a side elevation view of the lower portion of the design illustrated in FIG. 1;

FIG. 4 is a side elevation view of the upper portion, in an inverted position, of the design illustrated in FIG. 1;

FIG. 5 is a bottom view of the design illustrated in FIG. 1 with the upper and lower portions assembled; and,

FIG. 6 is a top view of the design illustrated in FIG. 1 with the upper and lower portions assembled.
